United States Patent Office

Des. 184,160
Patented Dec. 23, 1958

184,160

TRACTOR

Charles L. Whiting and Delmar D. Berckhan, Waverly,
Iowa, assignors to Schield Bantam Company, Waverly,
Iowa, a corporation of Iowa

Application January 13, 1958, Serial No. 49,213

Term of patent 7 years

(Cl. D14—3)

FIG. 2

Fig. 1 is a view in perspective from the front of the tractor showing our new design; and

Fig. 2 is a view in perspective from the rear of the tractor.

The side opposite that disclosed is substantially the same in appearance as the side shown.

The dominant features of the design are shown in full lines.

We claim:

The ornamental design for a tractor, as shown and described.
